UNITED STATES PATENT OFFICE

152,208

DESIGN FOR LENS RIM MATERIAL FOR SPECTACLE FRAMES

Martin J. O'Dea, Rochester, N. Y., assignor to
Bausch & Lomb Optical Company, Rochester,
N. Y., a corporation of New York

Application March 12, 1947, Serial No. 137,544

Term of patent 14 years

(Cl. D57—1)

To all whom it may concern:

Be it known that I, Martin J. O'Dea, a citizen of the United States and a resident of Rochester, county of Monroe, and State of New York, have invented a new, original, and ornamental Design for Lens Rim Material for Spectacle Frames, of which the following is a specification, reference being had to the accompanying drawing, forming a part thereof.

Fig. 1 is a front view of a portion of lens rim material for spectacle frames, showing my new design.

Fig. 2 is a top view thereof.

Fig. 3 is a rear view thereof.

Fig. 4 is a sectional view taken on lines 4—4 of Fig. 1.

Fig. 5 is a sectional view taken on line 5—5 of Fig. 1.

The characteristic feature of the design resides in the series of scallops which are formed

on the rear sides of the lens rims which are substantially transparent. With this design, light ray reflections from the polished surfaces of the scallops are visible through the lens rims.

I claim:

The ornamental design for lens rim material for spectacle frames, substantially as shown and described.

MARTIN J. O'DEA.
